OIL BURNER PRIMARY SAFETY CONTROL

Albert L. Judson, Portland, Oreg., assignor to
Iron Fireman Manufacturing Company, Port-
land, Oreg.

Application June 20, 1949, Serial No. 100,131

3 Claims. (Cl. 158—28)

1

This invention relates generally to electrically operated and controlled oil burners and more particularly to the circuits controlling the driving motor and the ignition mechanism of such a burner.

Considered broadly, the present invention has for its purpose the provision of an oil burner primary control having a simple and easily understood circuit scheme and yet which will be reliable in operation and include the several desirable safety features which such a control should have.

It is a further purpose of this invention to provide a control scheme and mechanism which is complete with all required safety features and includes the feature of intermittent ignition well known in the art.

A further purpose is to provide such a scheme and mechanism which can be simplified by leaving out the ignition circuit and connecting the ignition transformer in parallel with the burner motor without eliminating any of the safety features of the control.

Still a further purpose is to provide such a scheme and mechanism which can be further simplified by the elimination of the transformer and its low voltage control circuit, and by placing the operating coil of the relay in the place normally held in the scheme by the primary winding of the transformer. From the figure it will be seen that this will result in a line voltage control much more compact and more economical to build than anything shown in the prior art and yet which will continue to include all the essential operational and safety features possessed by the more complete control. In the simplified control the line voltage limit control positioned as shown in the figure becomes the operating control or pilot instrument.

How my improved oil burner primary control is arranged and the advantages thereof will be apparent from the following description referring to the attached drawing in which the single Figure 1 is a conventionalized diagram showing the mechanisms of the control positioned in the circuits thereof.

Referring to the figure, there is shown a combustion chamber connected by a smoke pipe to a chimney. For purposes of description it is assumed that the combustion chamber is surrounded by a chamber through which is circulated a heating medium such as air or water which is transported in the usual way to a space to be heated. The thermostat is assumed to be in the space or medium whose temperature is to be con-

2

trolled and the limit control is assumed to be so actuated as to be responsive to the temperature of the heating medium surrounding the combustion chamber.

As shown in the figure, tension spring 62 through lever 46, adjustable fulcrum 61, and lever 59 biases temperature insensitive stem 41 toward the smokepipe where it engages on the inner end of temperature sensitive tube 40. As the temperature in the smokepipe increases, stem 41 recedes into the smokepipe and the left end of lever 46 is moved downward by spring 62. As the temperature in the smokepipe decreases, tube 40 contracts forcing stem 41 downward and the left end of lever 46 upward against the bias of spring 62. The relative movements of stem 41 and lever 46 is adjustable by right or left movement of fulcrum 61 and is indicated by pointer 54 on scale 55. Held in lever 46 are friction blocks 52 which frictionally engage stem 43 and cause stem 43 to travel with lever 46 within the range of movement determined by the adjustable stop 65 in the cooling direction and by the limit of throw of resilient switch arm 148 in the heating direction. Resilient switch arm 148 is biased toward the open position of contact pairs 172—137 and 272—273. Switch arm 148 and associated moving contacts 172, 272, and stationary contacts 137, 273 form, therefore, a two circuit single throw switch which is responsive to the increase or decrease of combustion temperature through the above recited system of levers.

The safety timing switch has two bi-metal blades 149 and 112 substantially parallel and similarly affected by ambient temperature. Additionally blade 112 is affected by its associated electric resistance heater 115, when the circuit in which the heater is connected is energized. Resilient blade 148 carries insulating rigid bar 176, to which it is riveted with silvered rivets. Bar 176 is secured with a hollow rivet to conducting resilient leaf spring 180. Leaf spring 180 is secured with silvered rivets to stiff conducting bridge 178. A depending tongue on bi-metal blade 149 inserts through slots in bar 176, leaf 180 and bridge 178 and bears laterally on bridge 178 to compensate for the effect of ambient temperature on blade 112 and therefore to maintain the proper relation of the right end of bridge 178 with the lower end of blade 112 with which it is normally engaged. When electric current passes through resistance heater 115 for a predetermined time, bi-metal blade 112 warps to the right and slides off the end of bridge 178 which is biased upward by both support 148 and leaf 180. When

this occurs the circuit from blade 148 to blade 112 is interrupted both at the junction of bridge 178 and blade 112 and by the separation of the rivet heads at the left end of bridge 178 from the rivet heads at the lower end of blade 148. To reset the switch it is necessary to allow blade 112 to cool and then manually to press the right end of bridge 178 downward until blade 112 can spring back into place over the right end of bridge 178.

The relay switch comprises three stationary contacts 134, 145, and 140 and three moving contacts 84, 96 and 90 carried respectively on resilient switch blades 83, 95 and 89. The relay operator comprises frame 184, coil 185, armature 186 hinged to frame 184 and toggle compression spring 194 biasing armature 186 to open position as shown. Operating lever 126 linked to armature 186 by adjustable stop screw 131 and arcuate spring 198 allows the switch contacts to close when coil 185 is energized and opens the switch contacts due to the action of spring 194 overcoming the bias of blades 83, 95, and 89 when the coil is de-energized.

The timing relay comprises resilient bi-metal blade 160 carrying moving contacts 166 and 167 and normally biased to close moving contacts 166 and 167 on stationary contacts 166a and 167a respectively. Associated with blade 160 is electric resistance heater 260 which, when energized, heats blade 160, causing it to warp upwardly and open switch contact pairs 166-166a and 167-167a.

In tracing the circuits of this control it is well to remember that the electric service line is connected to terminals 101 and 102. Terminal 101 is usually considered the "hot" terminal and 102 the "ground" terminal. The limit control or other high voltage pilot instrument if used is usually connected into the "hot" wire leading up to terminal 101. Inside the instrument of the present invention it is simplest to trace the circuits starting from terminal 101 and proceeding to terminal 102. The circuits included in the complete control are:

A first circuit including wire 142, wire 139, contacts 140, 90, relay switch blade 89, wire 85, terminal 103, and the burner motor having its other terminal connected to terminal 102.

A second circuit including wire 142, bi-metal blade 160, contacts 166, 166a, wire 265, blade 148, bridge 178, blade 112, heater 115, wire 117, 200 and the primary winding of transformer 74 whose other terminal is connected to terminal 102 by wire 199.

A third circuit which includes wire 142, bi-metal blade 148, contacts 172, 137, wire 132, relay switch contacts 134, 84 and blade 83 connected to wires 117 and 200.

A fourth circuit including wire 142, bi-metal blade 148 contacts 272, 273, wire 261, and heater 260 whose other terminal is connected to terminal 102 by wire 262.

A fifth circuit which is a low voltage control circuit complete in itself and which includes the secondary winding of transformer 74, wire 202, relay coil 185, wire 203, terminal 105 to which is connected a thermostat or other pilot instrument, terminal 106, and wire 201 back to the other side of the transformer secondary.

A sixth circuit which includes wire 142, bi-metal blade 160, contacts 167, 167a, wire 144, contacts 145, 96, blade 95, wire 91, and terminal 104 between which and terminal 102 is connected the ignition transformer of the oil burner control system.

From the drawing it is evident that the control can be simplified by eliminating the sixth circuit and connecting the burner ignition apparatus in parallel with the burner motor between terminal 103 and 102.

Also from the drawing it is evident that the control can be further simplified by eliminating the transformer and the fifth circuit and connecting the relay coil 185 in the place in the 10 second circuit shown for the primary of the transformer. In this case the limit control would become the pilot instrument or, if desired, a line voltage thermostat or additional pilot instrument can be connected in the service line leading up to terminal 101.

As shown schematically in the drawing the oil burner is not in operation since the thermostat is satisfied and open. Assume then that the thermostat cools off and closes, thus indicating a need for the generation of additional heat. The primary transformer 74 is energized from lines 101 and 102 through the timing relay contacts 166, 166a and through the safety timer. When the thermostat closes relay coil 185 is energized from the secondary coil of transformer 74 and the secondary load reflected in the primary circuit starts resistor 115 of the safety timer to heat up. Also armature 186 is attracted by coil 185 and rocks lever 126 and allows relay blades 83, 95, 89 to close their respective pairs of relay contacts. The burner motor is energized from lines 101 and 102 through relay contacts 90, 140. The burner ignition system is energized from lines 101, 102 through timing relay contacts 167, 167a and relay contacts 95, 96. Supposedly then the burner is in operation and hot products of combustion are being formed in the combustion chamber and beginning to find their way through the smoke pipe to the chimney 40 and heating heat sensitive sleeve 40 on the way. As sleeve 40 heats it expands inwardly of the smoke pipe taking with it heat insensitive rod 41 which through the system of levers shown allows spring 62 to pull the left end of lever 46 down taking with it stem 48 engaged by friction blocks 52. Stem 48 pressing on lever 148 closes stack element contacts 172, 137 and 272, 273. As seen from the drawing the closing of contacts 172, 137 completes a second circuit from lines 101, 102 through the primary of transformer 74 via relay contacts 84, 134 and therefore makes the safety timer ineffective to open the primary circuit. The closing of contacts 272, 273 energizes timing relay resistor 260 from lines 101, 102 which after a short delay heats bimetal 160 sufficiently to open contacts 166, 166a and 167, 167a thereby deenergizing the ignition system, taking the safety timer out of circuit and leaving the burner in normal operation.

Now assume that during this ignition period no ignition occurred or for any reason element 40 was not heated by the products of combustion. Then spring 62 could not have closed 55 contacts 172, 137 and 272, 273. The timing relay would not have operated, the ignition system would continue to operate and the resistor 115 of the safety timer would heat bimetal 112 until it moved away from bridge 178 and thus allowed the safety timer to break the transformer primary circuit and completely deenergize the control, shutting down the burner. In this case bridge 178 of the safety timer would have to be reset in position on the end of blade 112 after 70 blade 112 had cooled sufficiently to return it to 75

a resettable position. Similarly if at any time when the burner is in normal operation, should the element 40 drop in temperature, thus indicating a combustion difficulty or "flame failure" the contraction of element 40 would force lever 46 to overcome the bias of spring 62 and raise stem 48 allowing contacts 172, 137 to open and deenergize the primary of transformer 74. In this case however the control could start a new starting cycle of its own accord as soon as timing relay blade 160 had cooled sufficiently to close contacts 166, 166a and again energize the primary of transformer 74 through the safety timer. Normal shutdown would, of course, be by the opening of the thermostat which would return the control circuits to the condition shown in the drawing.

It should be noted that by a pre-determination of the resistance of the timing relay heater 260 and its thermal location with respect to the bi-metal blade 160 of the timing relay a desirable adjustment of the delay in the operation of the timing relay with respect to the operation of the combustion responsive switch is made possible.

Having thus described the mechanism, circuits, and use of the present invention with respect to the prior art, I claim:

1. In a control system for an oil burner, a first circuit including a first pair of relay switch contacts and a burner motor, a second circuit including a first pair of timing relay contacts, a normally closed safety timing switch having an electrically energizable actuator, and the primary coil of a transformer, a third circuit including a first pair of combustion responsive switch contacts and a second pair of relay switch contacts, a fourth circuit including a second pair of combustion responsive switch contacts and an actuator for said timing relay, a fifth circuit including the secondary coil of said transformer, an actuator for said relay, and condition responsive means for closing said fifth circuit to energize said relay actuator, a sixth circuit including a second pair of timing relay contacts, a third pair of relay switch contacts, and ignition means for said burner, said first, second, fourth, and sixth circuits being connected in parallel across a source of electric power, said third circuit being connected in parallel with that part of said second circuit which includes said first pair of timing relay contacts and said safety timing switch, means for closing said relay contacts when said relay actuator is energized and for opening said relay contacts when said relay actuator is de-energized, means for opening said timing relay contacts when said timing relay actuator is energized and for closing said timing relay contacts when said timing relay actuator is de-energized, and means responsive to an increase in combustion temperature to close said combustion responsive switch contacts and responsive to a decrease in combustion temperature to open said combustion responsive switch contacts.

2. In a control system for an oil burner, a first circuit including a first pair of relay switch contacts and a burner motor, a second circuit including a pair of timing relay contacts, a normal-

ly closed safety timing switch, having an electrically energizable actuator and the primary coil of a transformer, a third circuit including a first pair of combustion responsive switch contacts and a second pair of relay switch contacts, a fourth circuit including a second pair of combustion responsive switch contacts and an actuator for said timing relay, a fifth circuit including the secondary coil of said transformer, an actuator for said relay, and condition responsive means for closing said fifth circuit to energize said relay actuator, said first, second and fourth circuits being connected in parallel across a source of electric power, said third circuit being connected in parallel with that part of said second circuit which includes said first pair of timing relay contacts and said safety timing switch, means for closing said relay contacts when said relay actuator is energized and for opening said relay contacts when said relay actuator is de-energized, means for opening said timing relay contacts when said timing relay actuator is energized and for closing said timing relay contacts when said timing relay actuator is de-energized, and means responsive to an increase in combustion temperature to close said combustion responsive switch contacts and responsive to a decrease in combustion temperature to open said combustion responsive switch contacts.
